Patented July 15, 1924.

UNITED STATES PATENT OFFICE.

AUBREY J. DRUMMOND, OF NEW YORK, N. Y., ASSIGNOR TO KUHNE IDENTIFICATION SYSTEMS, INC., A CORPORATION OF NEW YORK.

METHOD OF TAKING FINGERPRINTS.

No Drawing.

Application filed February 24, 1922. Serial No. 539,028.

To all whom it may concern:

Be it known that I, AUBREY J. DRUMMOND, a citizen of the United States, residing at New York city, in the county of New York and State of New York, have invented 5 certain new and useful Improvements in Methods of Taking Fingerprints, of which the following is a specification, reference being had therein to the accompanying 10 drawing.

My invention relates to improvements in taking impressions such as finger prints, palm prints, foot and toe prints, etc., and more particularly has reference to taking 15 such impressions by substantially invisible and unobjectionable means.

For this purpose, instead of placing the fingers upon a surface which has previously been inked, the fingers may be placed upon 20 a surface which has been otherwise treated or prepared, after which the more or less invisible impression may be developed with colored value for discernment and permanent record.

25 To this end, I have found that by mixing a salt of silver, copper, mercury, bismuth, or oleate of lead with balsam of copaiba in the proportions of about one ounce of the former to $\frac{1}{4}$ ounce of the latter, an excellent 30 substitute for the unclean and obnoxious ink can be had. This may be rolled upon a surface if desired much in the same manner that ink has heretofore been applied to the surface, and after this has been done, the 35 fingers of the person whose impression is to be taken may be placed thereon and may be then placed upon a card or other surface, the impression being transmitted from the fingers to the card.

40 A second solution such as sulphide of ammonia or sodium sulphhydrate or any soluble sulphide in the proportion of about one of the salt to about 100 of water, may be now applied by dipping or atomizing preferably, or by camel's hair brush, with result 45 that the impression taken will be brought up in a permanent visible record suitable for filing.

Of course it will be understood that cards, 50 sheets, or other suitable records may be prepared with suitable material, and the impression may be made directly thereupon, after which the surface upon which the impression is made may be suitably developed 55 or otherwise treated by heat to render visual

the non-visual impression thus made instead of making an original impression, then transferring it and developing it as first stated.

This method of registering finger prints 60 is not only convenient, economical and expeditious, but is particularly unobnoxious and desirable in commercial institutions such as banks and other institutions especially where the finger prints of ladies, gentlemen, or children are to be recorded. One of the drawbacks in finger printing has been the soiling of the hands and the fact of its more or less exclusive association with matters of criminal record, whereas it is believed that with a less objectionable method 70 of registering finger prints, the value of such record in various commercial and social aspects will become more apparent, and less embarrassing, so that such records will become more general with the result that the identity of persons meeting with sudden death, etc., will be more certain of identification.

Of course it will be understood that various 80 modifications may be made in the proportions and ingredients used and in the method of practicing the invention without departing from the spirit of the invention as claimed.

I claim:

1. The method of taking impressions of the character described consisting in first preparing a surface with material adapted to adhere to the part to be impressed, then 90 impressing said part thereupon, thereafter impressing said part upon a receiving surface, and thereafter treating said surface with a substantially colorless material to visualize to greater degree the record 95 thereon.

2. The method of taking impressions of the character described consisting in first preparing a surface with material adapted to 100 adhere to the part to be impressed, then impressing said part thereupon, thereafter impressing said part upon a receiving surface, and thereafter treating said receiving surface to chemically establish to greater degree the impression thereon.

3. The method of taking impressions of the character described consisting in first preparing a surface with material adapted to 110 adhere to the part to be impressed, then impressing said part thereupon, thereafter

impressing said part upon a receiving surface, and thereafter chemically treating said receiving surface thereby chemically changing the material impressed.

4. The method of taking impressions of the character described consisting in first preparing a surface with substantially invisible transferable material adapted to adhere to the part to be impressed, then impressing said part thereupon, then impress-

ing said part upon a receiving surface thereby transferring said material to and leaving the same upon said receiving surface, and thereafter chemically transforming said material into a substantially permanent and ¹⁵ more visual record.

In testimony whereof I hereunto affix my signature.

AUBREY J. DRUMMOND.
